DIESEL ENGINE

Frederic W. Plumb, Huntington, N. Y.

Application July 27, 1942, Serial No. 452,430

11 Claims. (Cl. 123—53)

My invention relates to fuel-oil-burning internal combustion engines of the Diesel type shown in my prior patent No. 2,237,113, of April 1, 1941, and my object is to provide a new and improved engine of this nature which may be readily fitted for war purpose use in air, water or land combat vehicles.

More particularly my present improvements relate to a novel engine construction having its cylinder bent midway of its length to form two sides of an equilateral triangle, with the angled pistons therein acting as heretofore in an opposed two cycle stroke, and each piston having a crank shaft provided with a gear wheel meshing with and jointly operating a gear wheel on a centrally located drive shaft, enabling change of the drive gear ratio when needed and the use of a large tubular shaft through which a gun or cannon may be discharged.

An essential feature of my improved construction is the provision in the engine block of an integral closed top cylinder wall spaced over the communicating meeting ends of the angled cylinder bore portions so as to form a common compression ignition chamber for the opposed pistons, completely enclosed within said block as in the straight cylinder chamber of my aforesaid patent, and thus insure the high compression of the combustion charges necessary in a true Diesel engine.

Another highly important feature of my new construction is the provision for using a low pressure fuel oil supply pump, permitting the use of suitable size fuel pipe lines to reduce frictional loss, and feeding successive fuel oil charges, by means of an independently operated injection plunger controlled by the engine speed, under an intensified pressure sufficient to positively insure the discharge of such fuel charges into the highly compressed air in the cylinder; my improved construction further providing means for a manual selective throttle control for varying the amount and timing of such fuel charges.

My improved construction permits the desired use of enlarged and more effective anti-friction bearings with forced oil lubrication for the moving parts, and is particularly designed for construction in complete engine unit sections each having a novel built-in crank shaft provided with interlocking means at its ends to engage with a like crank shaft of an added engine section so as to facilitate multiple assembly of such sections for required power needs. My construction also provides for a usual water cooling system for the engine and cylinders, but of increased size

and efficiency with engine driven means for insuring water circulation therein.

My improved engine construction, and the manner of its use and multiple assembly with its manifest more efficient operation and ready adaptability for war needs are more fully described hereinafter in connection with the accompanying drawings, and the novel features thereof pointed out in the appended claims.

10 Fig. 1 is an end elevation of an engine showing a preferred embodiment of my improvements, a portion of the gear cover plate being broken away to show the enclosed gears.

15 Fig. 2 is a top plan view of the engine shown in Fig. 1.

Fig. 3 is a sectional elevation on the line 3—3 of Fig. 2.

20 Fig. 4 is a fragmentary flat-developed cross section on the line 4—4 of Fig. 3, showing the mounting of the main drive shaft.

Fig. 5 is a detail plan view taken substantially on the line 5—5 of Fig. 3, and showing the ribbed water jacket extension covering the compression-ignition chamber portion of the bent cylinder.

25 Fig. 6 is a vertical cross section taken on the line 6—6 of Fig. 3, showing one crank case and its communicating cylinder bore in axial section and the intermediate compression-ignition chamber 30 of the cylinder with its superimposed housing for the fuel injecting mechanism in medial vertical section.

Fig. 7 is an enlarged fragmentary end view of the fuel-injection housing, looking in the direction of arrow 7 of Fig. 6.

Fig. 8 is a correspondingly enlarged cross sectional view of the housing taken on the line 8—8 of Fig. 6.

40 Fig. 9 is a correspondingly enlarged sectional plan view of the housing taken on the line 9—9 of Fig. 6.

Fig. 10 shows in the broken away and separated upper portion a front elevation, and in the lower portion a longitudinal vertical section through their near crank case chambers, of a multiple assembly of three engine units and indicating means for connecting them for joint operation.

45 Fig. 11 is a fragmentary detail view, on a larger scale, showing the pre-combustion chamber for the fuel oil, above the cylinder compression-ignited chamber, for igniting such compression charge.

Referring to the drawings, my engine block is shown as a casting, preferably of a dense, uniform, wear resistant cast iron alloy, such as

that well known and commonly used under the name of Meehanite or like metal, and machine finished to form two upwardly inclined closed-top cylinder bores 5, 5, each opening at its lower end into a crank case chamber 6, 6, the lower half portions 7, 7, of the latter being separately formed and removably secured to facilitate entry of pistons 8, 8 into the cylinder bores 5, 5, and the mounting of crank axles 9, 9, having rods 10, 10 connecting their crank pins 9', 9', to their respective pistons 8, 8.

It will be seen that the longitudinal axes of bores 5, 5, form the side legs of an equilateral triangle, the base leg of which extends between the axial centers of the crank shafts 9, 9, and the upper contiguous walls of said bores 5, 5, meet below their common integral top closure wall 11 so as to form a compression ignition chamber portion 12 connecting said bores and providing for the latter operating as a continuous cylinder in which the pistons 8, 8 may act in an opposed relation and a two cycle stroke as in my aforesaid patent No. 2,237,113. This integral top cylinder wall 11 securely enclosing the compression-ignition chamber 12 uniting the bores 5, 5, is an important feature of my improved construction and a practical necessity in this Diesel type of engine to provide a leak-proof closed compression-ignition space between the advancing pistons with ample strength to withstand the high compression of the combustion charges in such space. This solid head construction avoids any need of a gasket required for a removable head and likely to cause leaks, and insures maintaining a constant compression ratio, say of sixteen to one which has been found to be most effective.

Each crank shaft 9, 9 is shown as having an end drive gear 15, 15, meshing with and jointly driving a gear wheel 16 on a main power shaft 17, shown as centrally mounted in the engine block between the angular cylinder bores 5, 5, and centrally within the aforesaid triangle, such location permitting the use of a large bore tubular shaft as shown through which a cannon or gun barrel may be discharged. This arrangement provides for substituting varying gears to change the ratio of drive of the power shaft for specific needs, and the latter may directly drive an air plane propeller or have a fly wheel and transmission mechanism for sea or land vehicles.

The engine block is shown with water jacket chambers 20, 20 encircling each cylinder bore 5, 5, with partition walls 21 therein separating parts of said chambers to form air passageways 22 extending from the respective crank case chambers 6, 6, to inlet apertures 23 in one cylinder bore 5, the opening and closing of which is controlled by the movement of its respective piston 8. The other cylinder bore 5 is shown with outlet apertures 24, discharging across the water jacket chamber and separated from the latter by partition walls 25. Each crank case chamber is shown with an air inlet opening 26 covered by a one-way acting valve plate 27 to admit air to said chambers where it is compressed and forced through air passageways 22 and cylinder inlet apertures 23. The angular arrangement of the cylinder bores allows the water jacket chamber to encircle a greater portion of the cylindrical chambers for more effective cooling, and this water jacket is shown at 28 as covering the top closure wall 11, and at 29 as encircling the chambers below their meeting passageway 12, which are the hottest portions of said chambers.

The top wall plate 11 is shown as having an upward circular-wall integral extension 30 forming a pre-combustion chamber 31, see Fig. 11, preferably having a nozzle and spiral director of the nature shown in my aforesaid patent, and acting to initially ignite therein only a portion of each fuel charge, which ignited portion then passes through the bottom opening of said chamber into the compression-ignition chamber 12 connecting the angled cylinder bores 5, 5, to ignite the remainder of the charge, without the shock of direct ignition of the entire charge. This circular wall 30 extends to the top of the water chamber 28 and has spaced parallel ribs 32 integrally uniting it to the top wall plate 11 and acting to strengthen the latter and aid in radiating heat to the adjacent water. The water chamber 28 is shown as closed by a cover plate 33, which also seats on the annular top edge of extension wall 30, and as the water is subjected to only light pressure, not affected by the high compression in the cylinder bores 5, 5, there is no problem involved in tightly securing the cover plate 33 against leakage.

The cover plate 33 is shown with spaced walls 40 and 41 closed at one end by an integral wall 42 of generally semicircular outline, and a separate cover plate 43 seats on the top edges of walls 40 and 41 and the free ends of the latter, so as to form a chamber 44 for the fuel-oil charge injecting pump mechanism later herein described. The wall 42 aforesaid, is apertured for a bearing extending therethrough from chamber 44 for a shaft 45 on which a drive gear 46 is mounted to mesh with and be driven by the gear 16 on main power shaft 17. A gear casing 47 is shown as covering the crank shaft gears 15, 15, main shaft gear 16, and gear 46, and this casing it will be seen has an outline formed by circles struck from the three apexes of the triangle aforesaid, and a circle struck from the axis of main power shaft 17, which is shown as the only shaft extending through this casing 47.

The opposite side of the engine block is shown as having a cover plate 50 for one crank shaft 9, carrying a suitable lubricating oil pump mechanism 51 driven by said crank shaft to supply lubricating oil under pressure to the moving parts. A similar cover plate 52 for the other crank shaft 9, is shown with suitable pump mechanism 53 driven by its crank shaft to circulate the water through the water jackets heretofore described. A third cover plate 54 encloses a bearing seat 55 in the engine block for the main power shaft 17, which extends through said cover plate.

The pre-combustion chamber 31 and its opening into the compression ignition chamber 12 connecting the meeting ends of the angled cylinder bores 5, 5, may desirably be similar to that shown in my aforesaid patent, but in the present construction I prefer to employ and show new and improved means for injecting the fuel oil charges into the highly compressed air in the cylinder, independent of the pressure for supplying the fuel oil, and permitting the use of an economical low pressure feed pump for the fuel oil, and, because of such low pressure feed, I may employ any ordinary suitable diameter feed pipe lines that will reduce friction to the oil flow. A usual low pressure rotary pump, such as a known Roper pump, is indicated at 60, and is shown as directly driven by a pump gear wheel 61 meshing with a pinion gear wheel 62 on gear wheel 46 driven by power shaft gear wheel 17. This pump

60 supplies fuel oil from a supply source, not shown, through feed pipe 63 to a chamber 64, as regulated by a by-pass valve 65, and from said chamber, through a check-valve guarded port 66 to a plunger controlled injection chamber 67, shown as having a free-floating ball check valve guarding its outlet to pre-combustion chamber 31. A charge injecting plunger 75, extending from a plunger guide 76, fitted to move in chamber 67, is shown as normally depressed by a leaf spring 77 and lifted from such depressed position by a bell-crank lever 78 carried by shaft 79. The bell-crank lever 78 is shown as intermittently operated in accordance with the speed of the engine by means of a trip cam 80 on a shaft 81 having a gear wheel 82 meshing with said pinion gear wheel 62 of gear wheel 45. Pump 60 forces fuel oil at low pressure to chamber 64, and, through port 66, to injection chamber 67 to keep the latter filled for action of the injection plunger 75 as determined by trip cam 80 on shaft 81. Leaf spring 77 determines the force with which plunger 75 is depressed, and its tension is independent of and permits low pressure of the fuel supply, and its tension may be varied by adjusting its clamped end or by addition to or removal of its component leaves, in accordance with the force of injection needed or desired.

The fuel oil injecting mechanism above described provides for feeding charges of fuel oil to the highly compressed air of the cylinder and in accordance with the speed of the engine, as it is operated by gear wheel 45 in direct mesh with power shaft gear wheel 17, and the leaf spring 77 regulating the pressure of the injection plunger, permits the use of a desirable low pressure feed pump for supplying the fuel oil to the injection chamber 67.

This new and improved fuel injection mechanism, as above described, permits the addition of a new and advantageous throttle control for regulating the amount of fuel oil injected by the plunger 75, and the timing of its injection action. This throttle control is provided for, as shown, by mounting bell crank lever 78 on an eccentric portion of its shaft 79, which latter is extended to project outwardly through a wall of injection chamber 44, and carries a hand lever 85 adjustably engaged with a notched sector 86. Swinging of hand lever 85 turns shaft 79 to change the center of throw of its bell crank lever 78 relative to plunger guide 76 so as to adjust the stroke of injection plunger 75 for any varying feed between a maximum and minimum fuel injection to the cylinder. And such shifting of the lever 78 also changes its relative position to cam 80 on shaft 81, changeably timing the cam operation on said lever between early and late limits and thus automatically regulating the timing of the fuel injection in accordance with the quantity determined by the plunger, and the speed of operation of the engine.

Only one fuel pump 60 will be required for a multi-assembly of my engine units, and only one hand control lever 85, but for such assembly, shafts 79 and 81 will preferably be extended to cover the number of engine units added, or such shafts may if desired be made in built-in sections with coupling units uniting them, as for my crank shafts, as later herein described.

The crank casing chambers 6, 6, are shown with wall bearings to receive the crank axles 9, 9, and the crank portions thereof are shown as made up of spaced discs counterbalanced if desired, and connected by eccentric crank pins 9', 9'. My 75

construction permits the use of large size anti-friction roller bearings for the crank axles 9, 9, as indicated, and these axles are shown as built into the engine unit, and their ends shown as formed 5 with three jaw clutches 90, 90, adapted to engage the ends of like crank shaft axles when other units are added and assembled to form a multi-cylinder engine. These sectional built-in crank shaft axles 9, 9, not only facilitate such multiple 10 assembly, but avoid the strains and distortions of expansion and contraction inherent where a single multi-cranked shaft is employed besides eliminating the costs of manufacturing and installing such varying length shafts; and the necessary strength for the clutch jaws 90, 90, of my 15 said sectional shafts is adequately provided for as by the duplex roller bearing rings 91 shown in Fig. 10 of the drawings.

My engine unit thus fully described is adapted 20 for multiple assembly as in my aforesaid prior Patent No. 2,237,113, but in this case a longer straight main power shaft 17, may be employed but is not always required and to employ suitable clamping means for connecting the crank shaft bearing bosses where they abut one another. Only one gear casing 41 is necessary, as only one 25 set of gears 15, 15, 17 and 46 are required in such multiple engine units, and such casing would be mounted on the outer face of an end unit, and the opposite end unit would carry cover plates 30 50, 52 and 54, as the pumps mounted on them would supply all the engine units, which may readily have suitable junction tubes connecting their respective water jackets and lubricating fuel systems.

In Fig. 10 I have indicated three-engine units 35 connected to form a multi-unit engine, such showing indicating how other engine units may be added by spacing the end units to form the end ones of any desired or required number. The built-in crank axles 9, 9, will interlock their jaw clutches 90, 90, so as to operate as a continuous 40 axle, the power shaft 17 may be extended if desired, but it is not required, as it is operated by its single gear wheel 16 of the train gears 15, 15, 16 and 45 on one end engine unit. Shafts 79 and 81 may be extended, or the separate engine sections thereof coupled together if desired 45 so as to extend across the multiassembly of engine units, with the throttle hand lever 85 located anywhere in its length. Coupling together of the several engine units is shown as simply and adequately secured as by using flanged connecting rings 95 engaging their abutted bearing bosses 96, 96. Nipples 97 may be used to connect the water jackets of the several units, and the crank cases may have an oil pipe 98 connecting them, and a branch pipe 99 from fuel oil pump 60 may carry fuel oil to the injection chamber of each engine unit.

My engine, as above described, forms a compact unit, readily assembled with minimum effort into a multiple unit engine, and operates as a true Diesel and in the powerful opposed pistons two-cycle stroke manner of my aforesaid Patent No. 2,237,113. It lends itself to ready installation of known large effective anti-friction bearings, and the use of known pump mechanism for lubricating oil and water circulation. Its generally triangular shape with the apex angle at the top forms little obstruction to sight in the case of a single propeller airplane. And the central location of its main power shaft permits use of a large tube for this purpose with a bore of sufficient size to receive a gun barrel of effective pow-

er, the barrel of which may be kept cool by the air passing through said tube, and this tubular power shaft may directly drive the propeller of an air plane, or may have a fly wheel and transmission mechanism as desired, or as required for other uses in sea and land vehicles.

My new and improved engine as herein fully described, is, so far as known to me, the first true Diesel engine employing a bent or angled cylinder, though I am aware that an attempt has heretofore been made along these lines without success or benefit in the art because of lack of understanding in essential and fundamental requirements of a true Diesel of the opposed piston two stroke cycle operation. In my improved construction I have retained all the essential requirements of such Diesel engine by making the angled portions of my cylinder with an integral closed compression ignition chamber, so that it will operate in the same effective manner as a straight cylinder heretofore believed necessary. In connection with the angled cylinder construction, I employ new and improved throttle controlled means for regulating the amount and timing of the injected fuel charges, making an engine unit of compact and economical construction, with easy access to all working parts, and of powerful efficiency, with ready adaptability for war needs. The particular detail embodiments shown and described may of course be modified within the scope of my invention as defined in the following claims.

What I claim is:

1. A two-cycle opposed piston engine of the compression-ignition internal combustion type, comprising an engine block having an internal angularly bent cylinder consisting of an intermediate compression-ignition chamber with opposite angularly extending piston bores completely enclosed within said block, a crank case extension and crank shaft for each cylinder bore, a fuel-injecting plunger opening into said compression-ignition chamber having a plunger operating drive shaft, the axes of said angular cylinder bores being coincident with two sides of an equilateral triangle, and the centers of the crank shafts and the plunger-operating drive shaft being coincident respectively with the apexes of the base and top angles of said triangle.

2. A two-cycle opposed piston engine of the compression-ignition internal combustion type, comprising an engine block having an internal angularly bent cylinder consisting of an intermediate compression-ignition chamber with opposite angularly extending piston bores completely enclosed within said block, a crank case extension and crank shaft for each cylinder bore, a fuel-injecting plunger opening into said compression-ignition chamber having a plunger operating drive shaft, a gear wheel on each of said shafts having their centers respectively coincident with the apexes of the three angles of an equilateral triangle, and an engine drive shaft at the center of said triangle having a gear wheel in engagement with the three gear wheels centered at said triangle apexes.

3. A two-cycle opposed piston engine of the compression-ignition internal combustion type, comprising an engine block having an internal angularly bent cylinder consisting of an intermediate compression-ignition chamber with opposite angularly extending piston bores completely enclosed within said block, a crank case chamber at the end of each piston bore, and a crank shaft section mounted in each crank case and

having an end coupling jaw adapted for removable connection of a shaft extension having a cooperating coupling jaw.

4. A two-cycle opposed piston engine of the compression-ignition internal combustion type, comprising an engine block having an internal angularly bent cylinder consisting of an intermediate compression-ignition chamber with opposite angularly extending piston bores completely enclosed within said block, a pre-ignition chamber communicating with said compression ignition chamber and extending upwardly from the top cylinder wall of the latter and having a spaced enclosing block wall so as to form a water circulating compartment, integral ribs connecting said walls and pre-ignition chamber so as to strengthen the same and form heat radiating fins, and a watertight cover plate for said compartment having an aperture communicating with said pre-ignition chamber.

5. A two-cycle opposed-piston engine of the compression-ignition internal combustion type, comprising an engine block having an internal bent cylinder consisting of an intermediate compression-ignition chamber with opposite angularly extending piston bores, pistons reciprocally mounted in said bores, crank case extensions for said bores having crank shafts connected to their respective pistons, a fuel-injecting mechanism for said compression-ignition chamber having a shaft operating a fuel oil pump and a fuel charge injecting plunger, a main engine shaft, having a gear wheel thereon, and gear wheels on said crank shafts and said fuel-injecting mechanism shaft intermeshing with said main engine shaft gear and disposed around the latter in a triangular relation so as to drive said main shaft and said injecting mechanism shaft in a cooperative timed relation with said crank shafts.

6. In the construction set forth in claim 5, a water-circulating jacket surrounding the bores and combustion-ignition chamber of said cylinder and having connections to a water circulating pump, one crank shaft having a shaft extension for driving said pump.

7. In the construction set forth in claim 5, a water-circulating jacket surrounding said cylinder bores and having partition walls forming an air passageway connecting said crank cases to one cylinder bore, an exhaust outlet from the other cylinder bore extending through the water jacket surrounding the latter, and one-way air-admission valves to the respective crank chambers.

8. In the construction set forth in claim 5, one crank shaft having an end coupling jaw, a shaft extension having a co-operating jaw engaging said coupling jaw, and a lubricating oil pump operated by said shaft extension and having oil flow connections to both crank case extensions.

9. A two-cycle opposed-piston engine of the compression-ignition internal combustion type, consisting of a plurality of like units cooperatively assembled for joint operation, each unit comprising a water-jacketed bent cylinder having an intermediate compression-ignition chamber with opposite angularly extending piston bores, and a piston in each bore operatively connected to a crank shaft mounted in a crank casing extension of said bore, a fuel injecting mechanism mounted over said compression-ignition cylinder chamber having an injection plunger opening to said chamber and a shaft

for operating said plunger, a main cam shaft mounted at a central location equidistant from each cam shaft and from said plunger operating shaft, intermeshing gears mounted on said shafts within a casing on the outer face of an end unit, each crank shaft having an end coupling engagement with the crank shaft of its adjacent unit, said plunger operating shaft cooperatively actuating the respective injection plungers of the respective fuel injecting mechanisms, a pump operated by one cam shaft for circulating water through the water jacket of all said cylinders, a pump operated by the other cam shaft for circulating lubricating oil to all of said crank cases, and means for simultaneously and determinedly controlling the amount and timing of the plunger injected fuel oil charges to the compression-ignition chambers of the respective cylinders.

20

10. A two-cycle opposed piston engine of the compression-ignition internal combustion type, comprising a triangular engine block having an internal bent cylinder with an intermediate compression-ignition chamber, a fuel injecting mechanism for the latter having a fuel-charge chamber, a low-pressure fuel supply pump for the latter, a fuel-discharge plunger in said fuel-charge chamber having a high-tensioned operating spring, and means for synchronously operating said engine comprising a central drive shaft with two crank-shafts and a fuel-mechanism operating shaft triangularly disposed around said drive shaft at the apexes of an equilateral triangle with intermeshing gears connecting said shafts.
11. In the construction set forth in claim 10, manual means for varying both the feed-stroke and timing of said spring operated fuel-discharge plunger.

FREDERIC W. PLUMB.
